OSCAR HAMMERSTEIN, OF NEW YORK, N. Y.

APPARATUS FOR APPLYING PROTECTIVE WRAPPERS TO CIGARS.

1,269,600.

Specification of Letters Patent. Patented June 18, 1918.

Application filed December 7, 1916. Serial No. 135,579.

To all whom it may concern:

Be it known that I, OSCAR HAMMERSTEIN, a citizen of the United States, and resident of the borough of Manhattan, city, county, and State of New York, have invented certain new and useful Improvements in Apparatus for Applying Protective Wrappers to Cigars, of which the following is a specification.

10 My invention relates to apparatus for applying protective wrappers to cigars and contemplates the provision of an improved and simplified apparatus whereby the final steps in applying said wrappers to the 15 cigars may be efficiently carried out and which will shape and form the pointed end of the cigar coincidentally with the application of the protective wrapper thereto. Other objects of my improvement will appear from the description hereinafter and the features of novelty will be pointed out in the appended claims.

Reference is to be had to the accompanying drawings which illustrate examples of 25 my improved wrapper and apparatus for applying same and in which Figure 1 is an elevation of my improved apparatus partly in section; Fig. 2 is a sectional view on the line 2—2 of Fig. 1; Figs. 2^a is a detail section on the line 2^a—2^a of Fig 1; Fig. 3 is a plan view partly in section; Fig. 4 is a detail plan view of a portion of said apparatus; Fig. 5 is a detail section on the line 5—5 of Fig. 3; Fig. 6 is a similar view on 35 the line 6—6 of Fig. 3; Fig. 7 is a face view of my improved wrapper and Fig. 8 is a perspective view of a cigar with my improved wrapper applied thereto.

As shown in the illustrated example my 40 improved apparatus comprises a table 10 carried by supports 11 which may either form integral parts of said table or comprise separate elements secured thereto in any suitable manner as by screws 12. The 45 said supports 11 are preferably fastened upon a base 13 for instance by means of screws 14, the base 13 in turn being preferably mounted upon legs or the like 15 in any well known or desired manner. The 50 apparatus further includes a sleeve 16 journaled in upright bearings 17 and 17^a located upon and secured to or forming part of the table 10, said sleeve 16 being continued beyond the bearings in one direction in the 55 form of a trough 18 as shown in Figs. 1 and 3. In order to prevent lengthwise movement

of the sleeve 16 in the bearings 17 and 17^a any suitable means may be provided as for instance a collar 19 located between the bearings 17 and 17^a and secured to the sleeve 60 16 in any convenient manner as by a pin 20. A plunger 21 is slidably mounted in the sleeve 16 and in its operative position projects beyond the same into the trough 18, the projecting end being preferably provided 65 with an adjustable head 22 which as shown in Fig. 3 may simply comprise a flat headed screw. At its opposite end said plunger 21 may be provided with an actuating device of any suitable character such 70 as a crank 23 having an operating handle 24. The plunger 21 in the illustrated example is connected to rotate with the sleeve 16 by means of a radially extending stud 25 which passes through registering slots 26 75 and 27 formed respectively in the sleeve 16 and collar 19, said slots being necessary to permit the plunger 21 to slide lengthwise in said sleeve 16 for the purpose to be more clearly brought out hereinafter. In addition to the above, I prefer to provide a projection 28 extending from the bearing 17^a toward the bearing 17 and adapted to cooperate with the stud 25 to bring the mechanism to a constant position of rest at the 80 completion of each operation as will also appear more fully farther on in the description. A clamping member 29 adapted to be moved into and out of registry with the trough 18 in any convenient manner is 85 provided and in the illustrated example is carried by an arm 30 pivoted at 31 to the lower surface of the trough 18. In the preferred form a finger piece 32 is formed on said clamping member 29 for facilitating 90 the operation thereof.

The apparatus further includes a shaping device 33 rigidly supported upon the table 10 and having a tapering or otherwise suitably shaped recess 34 upwardly open and 100 located in axial alinement with the trough 18 and having its opposite ends also open, the largest end of said recess being in close proximity to the free end of said trough as shown in Figs. 1 and 3. With the arrangement described the recess 34 forms substantially a stationary continuation of said trough the purpose of which will appear as the description proceeds. The small open end or apex of the recess 34 terminates in 105 the end wall of the device 33 and is in communication with a notch 35 extending trans-

versely to the recess 34 as shown in Figs. 1 and 2.

A tamping and forming member 36 provided with a recess 37 shaped to correspond to the form of the recess 34 and occupying an inverted position with respect thereto, is arranged to be reciprocated in a vertical direction in registry with the device 33 and so as to maintain the recess 37 in alinement with the recess 34. In the illustrated example of my improved apparatus, said member is carried by a rod 38 extending downwardly through a suitable opening 39 in the table 10 and vertically 15 slidable in a suitable bearing 40 depending from said table in registry with said opening 39. Any suitable mechanism may be provided for moving said rod 38 to reciprocate the member 36; for instance the illustrated arrangement may be adopted. This arrangement comprises one or more links 41 pivotally connected at one end with the lower end of said rod 38 as indicated at 42 and passing through an opening 43 formed 20 in the base 13, said links 41 being similarly connected at 44 with an arm 45 secured upon or forming part of a shaft 46 journaled upon the legs 15. The construction further includes an actuating lever 47 dependent from said shaft 46 and fixed thereon, said lever 47 terminating near the surface upon which the apparatus stands and being provided with a treadle or foot piece 48. I further provide an adjustable stop 25 of any convenient type to arrest the downward movement of the member 36 which stop, in the illustrated example comprises a screw 49 extending through a portion of the member 36 and arranged to contact 30 with the upper surface of the device 33 as will be clear from an inspection of Figs. 1 and 2.

My improved wrapper which is preferably used in combination with my apparatus comprises a sheet of paper or other suitable material having a main portion 50 and an end portion 51 of increased width and preferably formed with side edges 52 diverging from said main portion 50 as shown in Fig. 7 35 the opposite end edges 53 and 54 being substantially parallel. It will of course be understood that my apparatus may also be employed to efficiently apply protective wrappers of existing types as will be clear 40 from the description hereinafter.

In practice the cigar as it is taken from the press or the like and with the pointed end unfinished is placed upon the portion 50 of the protective wrapper and then rolled up 45 in said wrapper, the rolling starting from the edge 53 and ending at the edge 54. As the cigar in the condition in which it is placed upon the protective wrapper is more nearly in the form of a true cylinder than after it 55 is finished the application or rolling up of

the wrapper is facilitated and a result of maximum neatness is produced with a minimum of effort and care. In cases in which the protective wrapper is applied to the previously finished cigar the latter owing to its 70 shape tends to roll in the arc of a circle so that great care and considerable skill is necessary in order to properly apply the protective wrapper.

After the cigar has been rolled up in the 75 protective wrapper the diverging ends 52 of the portion 51 will project beyond opposite ends thereof, it being understood that the width of the main portion 50 corresponds approximately to the length of the cigar, so 80 that the side edges of said portion 50 register substantially with the opposite ends of said cigar, although this is not absolutely necessary. Thus at the end of the first step in the application of said protective wrapper a 85 minimum amount of material projects beyond the ends of the cigar so that the twisted ends into which these projecting portions of the wrapper are formed to complete the operation of applying the latter are of a minimum bulkiness and present a neat appearance. After the cigar has been manually rolled up in the wrapper as described the combined wrapper and cigar are placed in the trough 18 with the end thereof which is 90 to be pointed resting in the recess 34 and the projecting portion of said wrapper at this end extending through and beyond the small end of said recess. After the wrapped cigar has been properly positioned in the apparatus the clamp 29, which has previously 95 been moved out of registry with the trough 18 to facilitate the location of the cigar therein, as shown by dotted lines in Fig. 3 is returned to its operative position as shown 100 by solid lines in said figure in which it serves to clamp the said cigar in said trough. The plunger 21 which may also have been previously moved in the sleeve 16 toward the right in Fig. 3 to permit the wrapped cigar 105 110 to be readily placed in the trough 18 is then pushed in the reverse direction in said sleeve until the head 22 engages the end of the wrapped cigar as shown in Fig. 1. That portion of the wrapper which projects 115 through the small end of the recess 34 is then held between the fingers of the operator substantially in axial alinement with the trough 18 and the handle 24 is turned. This brings about a rotation of the sleeve 16, trough 18, 120 plunger 21 and head 22 and also causes a rotation of the wrapped cigar a pressure being exerted upon the plunger 21 toward the left in Fig. 3 to maintain the end of the wrapped cigar in the recess 34. As the parts 125 are rotated as described the said end will be rotated in said recess 34 and the projecting portion of the wrapper will be twisted as shown at *a* in Fig. 1, owing to the fact that this projecting portion is held stationary by 130

the operator. During the operations so far described the lever 47 may be periodically moved backward and forward by the operator through the medium of the foot piece 5 or pedal 48 whereby the shaft 46 is rocked in its bearings and thus, by means of the link or links 41 causes the rods 38 to be reciprocated in the bearing 40 in a vertical direction. Each downward movement of said rod 38 10 will bring the tamping or forming member 36 or more particularly the recess 37 thereof into engagement with the end of the wrapped cigar which is located in the recess 34. Through the coöperation of the recesses 34 15 and 37 and the tamping action of the member 36 the said end will thus be pointed or otherwise shaped and brought to a finished condition, the final shaping of this end of the cigar depending upon the shapes of said 20 recesses 34 and 37. The finishing of said cigar at this end and the applying of the wrapper is thus coincidentally carried on thus resulting in a saving of time and labor and bringing about a neater and more efficient winding of the wrapper.

As soon as the end *a* has been properly twisted and the tamping and forming operations have been sufficiently carried out the twisted end *a* is bent at an angle to the axis 30 of the cigar into the notch 35 as shown diagrammatically in Fig. 6, and is held therein by the operator. A continued actuation of the apparatus will now cause this twisted end *a* to be drawn through the notch 35 and 35 spirally wound upon itself as indicated at *b* in Fig. 8 whereby the application of the wrapper at the pointed end of the cigar is finished. Owing to the fact that the end *a* is easily held in the notch 35 and is thus 40 efficiently guided and maintained under a tension a neat and finished spiral of relatively small bulkiness is produced whereby the appearance of the package is enhanced and the pointed end of the cigar is protected. 45 When the above operations have been completed the plunger 21 is moved to the right in Figs. 1 and 3 to move the head 22 away from the cigar and the handle 24 is actuated until the stud 25 engages the projection 28 50 from below in which condition of the parts the trough 18 is in the normal position of rest shown in Figs. 1 and 3. The coöperation of said stud 25 and projection 28 thus efficiently stop the apparatus in a position of 55 rest which is constant and in which all parts thereof are readily accessible for the intended purposes. The wrapped cigar may now be readily removed from the apparatus by first swinging the clamp 29 to the position 60 indicated by dotted lines in Fig. 3 after which the projecting portion of the wrapper at the large end of the cigar may be straightened out and twisted by hand for instance as shown at *c* in Fig. 8 to complete 65 the package or otherwise finished.

In the finished condition the protecting wrapper is thus efficiently combined with the cigar in an attractive manner and so as to fully protect the latter and yet is readily removed when it is desired to smoke the 70 cigar. The particular shape of my improved wrapper, as before stated, reduces the bulkiness of the twisted portions at opposite ends of the cigar and at the same time 75 economizes in material. It will of course be understood that any existing type of wrapper may also be applied to a cigar as described with the assistance of my improved apparatus. The latter in itself is 80 extremely simple in construction and operation and makes it possible for unskilled labor to apply the protective wrapper with a maximum of efficiency and a minimum expenditure of time and effort. By adjusting the head 22 the apparatus may be arranged 85 to accommodate cigars of varying length, it being obvious that in some cases said head may be fixed or even entirely omitted in which case the inner end of the plunger 21 would be used to abut against the cigar. 90 The plunger 21 in addition to its other functions provides a simple medium whereby the one end of the cigar and wrapper may be efficiently maintained in the recess 34.

Various changes in the specific forms 95 shown and described may be made within the scope of the claims without departing from the spirit of my invention.

I claim:

1. An apparatus of the kind described 100 comprising a stationary shaping device having a tapering recess open at both ends, a carrying trough located in axial alinement with said recess, a rotatable sleeve forming a continuation of said trough, bearings for 105 said sleeve, a plunger slidably mounted in said sleeve and connected therewith, said plunger extending into said trough, and an actuating handle connected with said plunger whereby the latter is moved lengthwise 110 in said sleeve and the plunger, sleeve and trough are coincidentally rotated relatively to said recess.

2. An apparatus of the kind described 115 comprising a stationary shaping device having a tapering recess open at both ends, a carrying trough located in axial alinement with said recess, a rotatable sleeve forming a continuation of said trough, bearings for 120 said sleeve, a plunger slidably mounted in said sleeve and connected therewith, said plunger extending into said trough, an actuating handle connected with said plunger whereby the latter is moved lengthwise in 125 said sleeve and the plunger, sleeve and trough are coincidentally rotated relatively to said recess, a forming member located above and in registry with said shaping device, a vertically movable rod carrying said forming member and means for recip- 130

roating said rod whereby said forming member is reciprocated vertically relatively to said shaping device.

3. An apparatus of the kind described comprising a table having an opening, an apertured base carrying said table, means for supporting said base, a stationary recessed shaping device located upon said table, bearings carried by said table, a sleeve 5 rotatably mounted in said bearings and provided with a slot, a trough forming a continuation of said sleeve, a plunger slidably mounted in said sleeve, a stud extending radially from said plunger through said slot 10 whereby said plunger and sleeve are rotatable together, an adjustable head carried by said plunger, an actuating handle connected with said plunger, a forming member located above and in registry with said 15 shaping device, a vertically movable rod carrying said forming member and extending downwardly through the table opening, a shaft journaled on said supporting means, an arm carried by said shaft, a link connecting said arm and said rod, a lever depending from said shaft and a foot piece on said lever whereby the latter is actuated to rock the shaft and vertically reciprocate the forming member relatively to the shaping 20 device.
4. An apparatus of the kind described comprising a recessed element adapted to receive one end of a partially finished cigar contained in a protective wrapper, means 25 whereby said cigar is rotated relatively to said element to complete the application of the protective wrapper at said end, and tamping means whereby said end of the cigar is finished coincidentally with the finishing of the wrapping operation.
5. An apparatus of the kind described comprising a device having a recess open at its outer end for the accommodation of a pro-

jecting portion of the protecting wrapper of a wrapped cigar and means for rotating 45 said cigar whereby said projecting portion of said wrapper may be twisted, said device having a transverse notch communicating with said open end for the accommodation of the twisted end of said wrapper, 50 whereby said twisted end may be coiled upon itself as said cigar is rotated to form a cushion at the one end thereof.

6. An apparatus of the kind described comprising a shaping device having a tapering recess open at both ends and provided with a transverse notch communicating with the small end of said recess, a cigar carrying trough arranged in axial alinement with said recess, a sleeve forming a continuation 60 of said trough, bearings for said sleeve, means for rotating said sleeve and trough relatively to said shaping device, a forming member located above and in registry with said shaping device and means for vertically reciprocating said forming member 65 relatively to said shaping device.

7. An apparatus of the kind described, comprising a shaping device having a tapering recess open at its tapered end for the 70 accommodation of a projecting portion of the protecting wrapper of a wrapped cigar, a cigar carrying trough arranged in axial alinement with said recess, means for rotatably supporting said trough and means for 75 rotating the latter whereby said projecting portion of said wrapper may be twisted, said device having a transverse notch communicating with said open end for the accommodation of the twisted end of the 80 wrapper, whereby said twisted end may be coiled upon itself as said cigar is rotated to form a cushion at one end thereof.

In testimony whereof I have hereunto set my hand.

OSCAR HAMMERSTEIN.
